STAND AND PLANTER COMBINATION FOR
FLOWERING PLANTS

Vernon L. Leydig, P.O. Box 1026, Atascadero, Calif.

Filed Dec. 15, 1959, Ser. No. 58,677

Term of patent 3½ years

(Cl. D35—3)

FIG. 1.

FIG. 2.

FIG. 3.

FIG. 4.

Fig. 1 is a top perspective view of a stand and planter combination for flowering plants showing my new design;

Fig. 2 is a top plan view thereof on a reduced scale;

Fig. 3 is a perspective view thereof on a reduced scale taken from the side opposite that shown in Fig. 1; and

Fig. 4 is a vertical sectional view thereof taken on line 4-4 of Fig. 2.

I claim:

The ornamental design for a stand and planter combination for flowering plants, as shown.
